DEVICE FOR REDUCING THE TENSION OF THE FILM IN CINEMATOGRAPHIC APPARATUS

Application filed March 8, 1929, Serial No. 345,648, and in France June 20, 1928.

This invention relates to the devices which are used for reducing the tension of the film in cinematographic apparatuses and particularly to the devices of the kind described in the application No. 223,822 filed the 3rd of October 1927.

The said devices comprise one or several friction surfaces whose position is selected in such manner that the portion of film included between one of the supplying toothed barrels revolving at a uniform rate and the respective unwinding or winding spool freely passes over this friction surface when it is loose and bears and rubs upon the said surface when it is taut.

The present invention relates more particularly to the friction surface or surfaces which are situated between the supplying drum or barrel located at the outlet of the channel, the cinematographic apparatus and the spool about which the film is going to wind itself, the said friction surfaces being used for braking the film when the same is drawn too quickly by the winding spool.

According to this invention, use is made of a rotary friction organ operatively connected to the said supplying barrel or drum so that its periphery will have imparted thereto a linear speed which will be proportional to the speed of the said barrel and consequently to that of the film.

This arrangement shows relatively to the use of unmovable braking surfaces, the advantage of avoiding the localized wear which takes place on the latter, as the contact points of the revolving friction organ with the film are continuously changing whilst the wear is very regularly distributed all round the said organ.

Moreover, on account of the proportionality existing between the rates or speeds of the film and the friction surface, the efficiency of the device remains constant whatever may be the rate at which the operator causes the apparatus to move.

The accompanying drawing shows, by way of example, an embodiment of the object of the invention.

Fig. 1 is a side elevation of the braking device.

Fig. 2 is a section made along the axis of a revolving braking organ.

1 denotes the projection apparatus; 2, the film; 3, the outlet delivery device which, for the sake of clearness, has been supposed to be of a diameter equal to the one of the braking drum or barrel 4; 5 and 6 are loose rollers; 7 is the winding spool; 8, a transmission of any sort, a chain for instance passing over toothed wheels 9 and 10 connected to the delivery device and the braking drum or barrel. The radius of the toothed wheel 9 being smaller than the one of the wheel 10 and the diameter of the braking drum 4 being equal to the one of the delivery or supplying device 3, the surface speed of the drum or barrel 4 is smaller than the speed of the film which is itself equal to the surface speed of the supplying device 3. Of course the supplying device and the braking barrel can be connected through any other transmission means so that their rates of rotation will constantly be proportional.

It is obviously possible to provide for several drums or barrels such as 4 and loose guiding rollers such as 5 and 6, disposed in such a manner that the film successively passes about the said drums or barrels in following a sinuous path, all of the said drums or barrels revolving at a same linear speed which is proportional to the one of the film. In a general manner, use is made of one or several barrels 4 the surface speed of which is somewhat less than that of the film, for example nine-tenths of the said speed, so that when the film comes into contact with the said drum or drums, the required braking action takes place. This braking action can also be obtained when the connection between supplying device 3 and the drum or barrel 4 is such that the surface speed of the barrel is in a direction opposite to that of the film. In this case, the surface speed of the drum or barrel 4 can be of any range.

Fig. 2 shows a preferred construction of the braking drums or barrels. 11 shows a shaft connected with two cheeks 12 and 13 which are provided with rings 14 made of a substance the coefficient of friction of which is high relatively to the film, such as india-

rubber, for example; 15 is an intermediate loose barrel the edges of which are approximately flush with the said rings and whose middle is of a smaller diameter, this drum 5 or barrel being adapted to limit the transverse curvature of the film under too high effects of tension.

The revolution is obtained by the fact that the shaft 11 is operatively connected either 10 to the delivery or supplying device 3, or to the driving mechanism (not shown) of the said device. The spacing apart of the rings 14 is such that the perforated edges of the film bear upon the said rings when the film 15 is stretched or taut.

I claim:

1. In a device for reducing the tension of the film in cinematographic apparatuses, the combination of a toothed supplying drum disposed at the outlet of the cinematographic apparatus and adapted to drive the film at an almost constant speed, a spool for winding the film, a rotary friction roller between the said drum and the said spool and upon which 25 the film passes and driving means adapted to cause the said friction roller to rotate with a peripheral speed which is different from the average speed of motion of the film and proportional to the said speed.

30 2. In a device for reducing the tension of the film in cinematographic apparatuses, the combination of a toothed driving drum disposed at the outlet of the cinematographic apparatus and adapted to drive the film at an almost constant speed, a spool for winding the film, a rotary friction roller between the said drum and the said spool and upon which 35 the film passes and driving means adapted to transmit the revolution of the said toothed drum to the said friction roller with a peripheral speed which is different from that of the said drum and proportional to the said speed.

45 3. In a device for reducing the tension of the film in cinematographic apparatuses, the combination of a toothed supplying drum disposed at the outlet of the cinematographic apparatus and adapted to drive the film at an almost constant speed, a spool for winding the film, a rotary friction roller between the said drum and the said spool and upon which 50 the film passes and driving means adapted to cause the said friction roller to rotate with a peripheral speed which is different from the average speed of motion of the film and proportional to the said speed, the said friction roller being constituted by a driven 55 shaft, two discs connected to the said shaft, friction rings upon the said discs, the said rings being disposed so as to support the perforated edges of the film and a barrel loose on the said shaft between the said discs and 60 the edges of which nearly merge with the 65

periphery of the said rings and the middle of which is of a smaller diameter.

In testimony whereof I have hereunto affixed my signature.

ETIENNE OEHMICHEN.
